Primary Examiner — Mojtaba Tehrani(57) **CLAIM**

We claim the ornamental design for a firearm, as shown and described.

DESCRIPTION

FIG. 1.1 is a right side elevational view of a firearm showing my new design;

FIG 1.2 is a left side elevational view thereof;

FIG 1.3 is a front rear elevational view thereof;

FIG 1.4 is a rear elevational view thereof;

FIG 1.5 is a top plan view thereof; and

FIG 1.6 is a bottom plan view thereof.

The broken lines in the drawings are shown for the purpose of illustrating portions of the firearm and form no part of the claimed design.
